UNITED STATES PATENT OFFICE.

ARTHUR W. CASH, OF DECATUR, ILLINOIS, ASSIGNOR OF ONE-HALF TO
ADAM H. IMBODEN, OF SAME PLACE.

PAPER-BAG AND TWINE HOLDER.

SPECIFICATION forming part of Letters Patent No. 279,333, dated June 12, 1883.

Application filed February 20, 1883. (No model.)

To all whom it may concern:

Be it known that I, ARTHUR W. CASH, a citizen of the United States, residing at Decatur, in the county of Macon and State of Illinois, have invented a new and useful Improvement in Paper-Bag and Twine Holders, of which the following is a specification.

My invention relates to appliances for holding paper bags in a convenient manner to be seen and selected by a grocer or other dealer using them, and for holding twine to be used in tying the same; and it consists in a device having several compartments, each adapted to hold a quantity of bags hung by their upper ends, tags displayed at each compartment to show the size of the bags there hung by their number, and a twine-receptacle, all constructed and combined as hereinafter described and claimed, reference being had to the accompanying drawings, in which—

Figure 1 is a side elevation, and Fig. 2 is a plan view, of my combined bag and twine holder in a circular form. Fig. 3 is a side elevation of the same invention, the bag-holder being a straight line.

The bags are held by pointed wire pins A, pushed through them near their top or mouth ends. These pins are horizontal to allow the bags to hang on them in bunches of one hundred each, as that is the way in which bags are put up at the factory. The points on the pins allow them to be pushed through the bags a few at a time; or the awl x, which is detachable from the bag-holder, may be driven through the whole bunch at once to form a hole, into which pin A may be inserted to save time in arranging the bags and to hang them uniformly. Near their middle the wires forming pins A are bent to a vertical position, forming posts b, whose top ends are secured in the main wire B of the frame. The posts b are long enough to allow space between pins A and the wire B for that part of the bags above the holes. Each pin is longer than the space between the posts, and at the angle of the pin and post the wire forming them is bent upward in a short curve, forming a hook, a, in which the point of the next pin rests to help support its load and to keep the bags from slipping off from it. The normal posi-

tion of the pin is shown at A', Fig. 2, in which it stands ready to receive bags. When the bags have been placed on it, the end of the pin is pressed over into the hook a, causing a little torsion on its post b, which keeps the pin 55 firmly in the hook.

In Figs. 1 and 2 wire B forms a complete circle, and the pins A are repeated until they also complete a circle. In Fig. 3 wire B is a straight line, and the pins A, while in use, 60 form a line.

C represents an upper wire of the frame, connected with the wire B by posts c, and D D are hooks thereon, situated, respectively, over the pins A to hold tags d, having numbers on 65 them to show at a glance the size of the bags below them.

E represents three wires or cords, provided with a hook at their upper ends and secured at their lower ends to the bag-holder, as a 70 means of suspending the same at some convenient point near where the bags are most used. This much of the description pertains to the bag-holder. The twine-holder combined with it consists of a simple wire basket, G, adapted 75 to receive a ball of twine, the end of which will hang out at any side between the staves of the basket, so that when the twine is drawn out it has no tendency to lift the ball out at the top of the basket. The basket is secured to 80 the bag-holder as a part thereof by the bracing-wires g, which may be extensions of the posts c. The benefit of this combination consists in having the twine and bags near together, the one being used with the other. 85

As bags of the same width are frequently made of different lengths, the necessity of the tags d to indicate the size of the bags is apparent. After bags are placed on the pins, and the proper tag to indicate each size is hung 90 over that size, and a ball of twine has been placed in the receptacle G, nothing further is required to operate the device than to pull down the bag required, allowing the pin to tear out of it and pull the amount of twine 95 required from the ball.

What I claim as my invention, and wish to secure by Letters Patent, is—

1. The combination, with the main wire B, of the series of wires forming the posts b, se- 100

cured to said wire B, bent to form the hooks *a*, and pointed to form the pins A, as shown and described.

2. The combination, with the main wire B, and the pins, posts, and hooks above described, of the upper wire, C, the posts *c*, connecting the same to the wire B, the hooks D, and the tags *d*, hung thereon and numbered to indicate the size of the bags below, as set forth.

3. The combination, with the bag-holding device above described, of the twine-basket G, secured thereto, as shown and described.

ARTHUR W. CASH.
